SPINNING CENTRIFUGE

Waldemar Zur Löwen, Wuppertal-Barmen, Germany, assignor to American Bemberg Corporation, New York, N. Y., a Corporation of Delaware

Original application August 11, 1931, Serial No. 556,428, and in Germany August 25, 1930. Divided and this application December 16, 1932. Serial No. 647,594

3 Claims. (Cl. 118—49)

My present invention relates to improvements in the construction and arrangement of an apparatus for the production of artificial silk and the like according to the "pot-spinning" process.

5 The invention hereinafter described constitutes a divisional application of Waldemar Zur Löwen, filed August 11, 1931; Serial Number 556,428. In that application mechanism is described whereby each filament guiding tube has an independent 10 drive thus reducing the number of operative parts and rendering the operation of the machine more efficient.

In the apparatus disclosed and claimed therein, the thread is distributed in a rotating spinning 15 pot or centrifuge by means of a reciprocating thread guide tube which passes into the spinning chamber through an opening formed in the cover thereof. The thread guide tube is actuated by the spinning pot or centrifuge motor 20 and is so constructed as to be swung from over the spinning chamber to permit the cover and thread cake to be readily removed.

However, due to the tendency of the thread 25 guide tube to be shifted by the high rate of rotation of the spinning pot during the spinning operation out of alignment with the vertical axis of the said spinning pot, the thread guide tube must be positioned with a high degree of accuracy concentric thereto. Any such shifting of the thread 30 guide tube will result in the formation of a poor thread cake.

It is, therefore, an object of my present invention to provide an improved construction for maintaining the thread guide tube concentric to 35 the axis of the spinning pot during the spinning operation.

Another object of my present invention is to provide an improved construction for locating the thread guide tube concentric with respect to 40 the axis of the spinning pot without necessitating complicated adjusting mechanism for the driving mechanism.

These and other objects of my present invention will become more apparent from a study 45 of the following description and by reference to the attached drawing in which:

Figure 1 is a view in side elevation of the apparatus, certain parts thereof being shown in section;

50 Figure 2 is an enlarged detail view of the conduit for the thread guide tube; and

Figure 3 is a similar view showing the arrangement of the driving mechanism.

Reciprocatory motion is imparted to the thread 55 guide tube 10 for distributing the thread in the

spinning pot 11 by the driving mechanism for the said pot in which is enclosed in the casing 12. The thread guide tube is operatively connected thereto by means of a shaft 13 having a horizontal extension to which the tube is secured by suitable clamping means 14. A sleeve 15 is attached to the lower end of said shaft and couples the shaft 16 thereto. This latter shaft may be reciprocated in any desired manner by the motor. After the spinning operation has 60 been completed, the shaft 13 is moved upwardly until the lower end of the thread guide tube is clear of the housing cover 19. The thread guide tube is then swung out of the way of the cover and is moved to a position to engage the lug 17 65 carried by the shaft 13 on the catch 18 carried by the bracket secured to the centrifuge housing.

Referring now to Figure 2, I have shown an improved construction for aligning the thread 70 guide tube concentric with respect to the axis 75 of the spinning pot. The opening 20 through which the thread guide tube enters the spinning pot is provided with a guide or fitting formed of two parts. The member 21 is provided with a shank 22, and a flange 23 which rests on the 80 cover. As shown, this member fits loosely in the opening in the cover and is secured in the desired position by the nut 24 threaded onto the shank portion 22. By this arrangement the guide or fitting may be adjustably positioned within 85 the opening in the cover thus providing means to locate at all times the thread guide tube concentric to the axis of the spinning pot.

While I have herein illustrated the invention 90 as embodied in a preferred form of construction 90 it is to be understood that various modifications may be made in the design and arrangement of the parts thereof without departing from the spirit or scope of the invention.

Therefore, without limiting myself in this respect, I claim:

1. In a spinning mechanism comprising a spinning pot, a housing therefor, a cover for said housing having an opening formed centrally therein, a reciprocating thread guide tube to distribute thread in said spinning pot, means to position said thread guide tube concentric to the axis of said spinning pot, comprising a guide in which said thread guide tube reciprocates and loosely fitting said opening and means to secure said 100 guide adjustably in said opening.

2. In a spinning mechanism comprising a spinning pot, a housing therefor, a cover for said housing having an opening formed centrally therein, a reciprocating thread guide tube to dis- 105

tribute thread in said spinning pot, means to position said thread guide tube concentric to the axis of said centrifuge comprising a guide in which said thread guide tube reciprocates and loosely fitting said opening, said guide having a flange resting on said cover and a shank loosely fitting in said opening, and means to secure said guide adjustably in position.

3. In a spinning mechanism comprising a spinning pot, a housing therefor, a cover for said housing having an opening formed centrally

therein, a reciprocating thread guide tube to distribute thread in said pot, means to position said thread guide tube concentric to the axis of said pot comprising a guide in which said thread guide tube reciprocates and loosely fitting said opening said guide having a flange resting on said cover, a threaded shank loosely fitting in said opening, and a nut threaded thereon to secure said guide adjustably in position.
